UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,213,952.

Specification of Letters Patent. Patented Jan. 30, 1917.

Application filed June 22, 1914. Serial No. 846,589.

To all whom it may concern:

Be it known that I, WILLIAM J. ROCHE, a resident of Meadville, in the county of Crawford and State of Pennsylvania, have 5 invented a new and useful Improvement in Garment-Stays, of which the following is a specification.

This invention relates to wire garment stays and more particularly to corset stays. 10 The object of the invention is to provide a flexible wire stay which yields readily in all directions, in which the bending strains are distributed over a considerable length of wire so as to avoid crystallization and deterioration of the metal and prevent the stay from taking a permanent set, and particularly a stay which is stronger and more resilient than prior stays.

The invention comprises the stay herein- 20 after described and claimed.

In the drawings, Figure 1 represents a face view of one form of stay embodying the invention; Fig. 2 is an edge view thereof; Fig. 3 is a cross section on the line 3—3, 25 Fig. 1; and Figs. 4 and 5 are face views of other forms of stay embodying the invention.

The stay shown in the drawings is formed from wire, a single continuous wire 1 being 30 shown, which is bent back and forth in sinuous form to form a series of oppositely disposed main loops or eyes 2 lying along the edges of the stay and which are connected by transverse or intermediate portions or 35 crossings 3. The main eyes or loops 2 may be substantially directly opposite each other as shown in Fig. 1, in which case part of the crossings, indicated at 3^a, lie substantially normal to the length of the stay, while the 40 other alternate crossings, indicated at 3^b, are all inclined to the length of the stay in the same direction, or, the crossing portions may be so arranged that the main eyes or loops 2 lie somewhat in staggered relation or with a 45 progressive arrangement, as shown in Figs. 4 and 5. The main eyes or loops 2 may all lie in the same flat plane, or, if desired, successive eyes or loops may overlap each other slightly longitudinally of the stay, as at 4, 50 to produce a shingled appearance when the stay is viewed edgewise, as shown in Fig. 2, which reinforces the stay and provides mutual support between the several eyes or

loops and enables them to pass each other readily when the stay is flexed edgewise. 55

To increase the length of wire in the stay as a whole and to stiffen it and make it more resilient as against bending strains, each of the crossing portions 3 is bent or deflected intermediate the edges of the stay to form 60 a loop, eye, or convolution 5. These loops or convolutions may all lie along the center line of the stay, but as shown, the loops in the crossings 3^a lie on one side of the center line of the stay, while the loops or convolu- 65 tions in the alternate crossing portions 3^b are on the other side of the center line of the stay, thereby forming two rows of small eyes or convolutions which lie adjacent to or within the main eyes or loops 2. These 70 small eyes or loops 5 may be of any suitable shape or size and may lie in various positions, either close to the center line of the stay or contained almost wholly within the main eyes or loops 2 and close to the edges 75 of the stay as shown in Fig. 4, and reinforce the stay against bending strains.

The intermediate portions or crossings 3 may be bent, kinked or deflected in any suitable manner. For example, all of said 80 crossings may be bent toward one flat side of the stay, to produce a stay which is concavo-convex in cross section, as shown in Fig. 3, which gives the stay greater resistance to bending in one flatwise direction 85 than in the other, as will be readily understood. Also, the crossing portions of the wire may be bent or deflected intermediate the edges of the stay and preferably along its central line, as indicated at 6, Fig. 4, to 90 form a series of loops or convolutions along the central line of the stay and thereby increase the length of wire therein and reduce the liability of crystallization and deterioration. 95

The main eyes or loops 2 may be open along one edge of the stay as shown in Fig. 1 or may be formed by inclining alternate crossing portions of the wire in opposite directions, as shown in Fig. 5, in which case 100 all of the eyes or loops are closed by the crossing portions of the wire, each eye or loop being a complete convolution.

The stay described contains considerably more wire for given dimensions than prior 105 stays and is materially reinforced by the

rows of small eyes, loops or convolutions along the middle portion of the stay. Consequently, it has a longer life and is not so liable to deteriorate or to take a permanent 5 set on short bends.

What I claim is:

1. A garment stay, comprising wire bent back and forth to form a series of eyes or loops along the edges of the stay and connecting crossings, the crossing portions being bent to form another series of smaller closed eyes or loops lying in the plane of the stay and between the edges thereof.
2. A garment stay, comprising wire bent back and forth to form a series of open eyes or loops along both edges of the stay and intermediate connecting portions or crossings, successive eyes or loops overlapping each other slightly, the crossing portions of the wire being bent to form another series of smaller closed eyes or loops lying in the plane of the stay and between the edges thereof.
3. A garment stay, comprising wire bent back and forth to form a series of eyes or loops and connecting crossings, said eyes or loops lying along the edges of the stay, the wire being also bent to form another series of complete coils lying along the middle portion of the stay and in the plane thereof.
4. A garment stay comprising wire bent

back and forth to form a series of open eyes or loops along both edges of the stay and connecting crossings, each crossing portion being bent intermediate the edges 55 of the stay to form a smaller closed eye or loop, the closed eyes or loops in alternate crossings lying on opposite sides of the middle line of the stay and in the plane thereof.

5. A garment stay, comprising wire bent 40 to form two series of open loops or eyes lying along the edges of the stay and a series of transverse crossing portions, the crossing portions being bent to form two parallel series of closed loops or eyes lying between the 45 edges of the stay and in the plane thereof.

6. A garment stay, comprising wire bent to form two series of loops or eyes lying along the edges of the stay and a series of transverse crossing portions, the crossing portions being bent to form two distinct 50 parallel series of smaller loops or eyes lying between the edges of the stay and each overlapping the next adjacent crossing longitudinally of the stay in the plane thereof.

In testimony whereof, I have hereunto set my hand.

WILLIAM J. ROCHE.
